WEB TENSIONING AND CONTROLLING MECHANISM FOR PRINTING MACHINES AND
THE LIKE

Application filed August 29, 1931, Serial No. 560,180, and in Great Britain October 22, 1930.

This invention relates to web tensioning and controlling mechanism for printing machines and the like.

It is well known that the controlling of the rate at which the paper or web is supplied to a printing machine is very important and is also difficult on account of the mass of the roll, its varying diameter and the speed at which the web has to pass to the machine. 60 Various arrangements of braking bands or aprons have been suggested, in some of which one end of the apron has been secured to a fixed point through springs and the other end attached to a drum capable of rotation to 65 vary the pull or tension on the apron.

The present invention relates to web tensioning and controlling mechanism of this general type.

According to this invention the apron drum, i. e. the drum to which one end of the apron or series of bands is attached, is coupled to its spindle through a spring, the spindle being rotated to vary the stress in the spring coupling and thus regulate the pull or tension on the apron.

The rotation of the spindle is preferably effected by an electric motor which may be manually controlled or automatically controlled in accordance with the tension of the web passing to the printing machine. The motor may be geared to the spindle by worm or other gearing which is preferably irreversible, i. e. although the motor can drive the spindle in either direction it cannot be driven from the spindle.

Normally the tension on the apron is varied through the spring coupling but in order that, when desired, as for instance when the printing machine is stopped quickly, the braking action of the apron on the web roll may be suddenly increased, mechanism is conveniently provided whereby the apron drum can be rotated independently of the spring coupling. This mechanism may be in the form of a pivoted catch lever or like device actuated, say, by a solenoid and is preferably so interlocked with switches controlling the main driving motor of the printing press that it is automatically brought into operation when the press is stopped.

Any suitable form of control system or arrangement may be provided for the electric motor driving the spindle so that the web tension can be varied in accordance with working conditions, but preferably a system which permits the web tension to be controlled from a remote point is employed.

In one convenient system, in accordance with a feature of this invention, the motor is controlled by a hand-operated controller and a device controlled in accordance with the web tension, such device acting to stop the motor when the position of the device corresponds to the position of the controller whereby the position of the controller affords a direct indication of the web tension. Preferably the device controlled by the web tension comprises a follow-up controller driven by the motor or by the drum spindle and adapted to open the circuit of the motor when the web tension corresponds to the setting of the hand-operated controller.

Each controller may be provided with a series of contacts, corresponding contacts of the two controllers being connected together. The follow-up controller then has a driven contact device so formed that it engages all but one of the contacts of the controller, the motor circuit being so connected to the two controllers that the motor is inoperative when the disengaged contact of the follow-up controller corresponds to the contact engaged by the handle on the hand-operated controller.

In another convenient system the motor is controlled by two switches, preferably of the push-button type, the two switches being arranged so to control the motor that when one switch is closed the motor rotates in one direction to increase the web tension whilst when the other switch is closed the motor rotates in the other direction to reduce the web tension. Conveniently the motor is provided with two oppositely wound field circuits, preferably connected in series with the motor armature, and the control switches are arranged so that the circuits of the armature and one field are completed by the operation of one switch and the circuits of the arma-

ture and the other field by the operation of the other switch.

In the case of a printing machine having a normal speed and a slow speed (for starting, making joins in the paper and other purposes) obtained by driving the machine respectively by a main motor and by an auxiliary motor, the switches controlling the selection of the speed may be provided with auxiliary contacts which are so associated with the control system of the tension motor that the web tension is reduced automatically to a predetermined value during slow speed running of the machine.

15 Thus when the control system having the hand-operated and follow-up controllers is employed, the auxiliary contacts are arranged so that during slow speed running of the machine the controller handle is rendered ineffective and the contacts of the controllers corresponding to the appropriate value of web tension are rendered operative to control the tension motor. When the push-button control system is employed the auxiliary contacts are arranged so that the motor operates automatically to reduce the web tension during the change from normal to slow speed and to restore it to the normal value during the change from slow to normal speed, limit 20 switches operated by the drum spindle or the motor preferably being provided to open the motor circuit when the web tension reaches the appropriate value.

35 The following is a description, by way of example, of one construction of web tensioning and controlling mechanism and of two forms of control arrangement therefor, according to this invention, with reference to the accompanying drawings, in which,

40 Figure 1 shows, diagrammatically, the general arrangement of a printing machine, its driving and control gear, and its web tensioning mechanism,

Figure 2 is a sectional side elevation of the 45 web tensioning mechanism on an enlarged scale,

Figure 3 is an end elevation of the web tensioning mechanism shown in Figure 2,

50 Figure 4 is a wiring diagram of the preferred form of control arrangement,

Figure 5 is a sectional side elevation of a follow-up controller for use in the control arrangement shown in Figure 4,

55 Figure 6 is a wiring diagram of another form of control arrangement, and

Figure 7 shows, in side elevation, a detailed view of switches employed in the control arrangement of Figure 6.

60 As shown in Figure 1 a printing machine X having rollers X^1 is positively coupled to a countershaft X^2 directly connected to a main motor X^3 and also connected through an overrunning clutch X^4 to an auxiliary motor X^5 . During normal operation the machine is driven by the main motor X^3 whilst the auxiliary

motor X^5 is used for starting and for slow speed running such as is required when, for example, a join is being made between the paper from a new web roll and that from the old roll which is almost emptied.

70 The motor X^3 is energized from supply mains Y Y^1 through a main switch Y^2 and starting control gear, indicated by the square Y^3 , of any suitable kind, the control gear Y^3 being provided with an auxiliary contact P^2 75 which is closed when the control gear is in the "off" or "start" position, and which is associated with the control apparatus for the web tensioning mechanism in a manner to be more fully described hereinafter. The motor X^5 is also energized from the mains Y Y^1 through a switch Y^4 and control gear Y^5 . The switches Y^2 and Y^4 are respectively provided with auxiliary contacts P and P^1 , the contact P being closed when its associated switch is open and the contact P^1 being closed when its switch is closed. These auxiliary contacts are associated with the control arrangement (indicated by the square D^3) of 80 the web tensioning mechanism.

85 The web Z for the machine X is supplied from a web roll Z^1 mounted in bearings on arms Z^2 forming part of a supporting frame (not shown) of any suitable form. The web Z passes from the roll over a guide roller Z^3 90 to the rollers X^1 of the machine. The tension of the web is controlled by a braking apron, or a series of bands, A^3 which engages the periphery of the web roll Z^1 and has one end connected by one or more adjustable springs A^7 to a fixed point A^8 and the other end attached to an apron drum A . The drum A is controlled, in a manner to be more fully described, by a tension motor D to vary the 95 pull or tension on the apron A^3 which acts in the well known manner to exert a braking effort on the web roll Z^1 and thus to vary the web tension.

100 Referring now to the more detailed views of the web tensioning mechanism shown in Figures 2 and 3, the apron drum A is mounted on bearings A^1 A^2 on a spindle B which can be rotated. The drum A is connected to the spindle B by means of a helical spring C 105 which encircles the spindle inside the drum and has one of its ends attached to an internal flange A^4 on the bearing A^1 and the other end to a collar B^1 keyed to the spindle B , there being sufficient space between the turns of the spring C to allow for an increase in the number of those turns when the spring is tightened by the rotation of the spindle.

110 When the spindle B is rotated the spring C is stressed and thus tends to rotate the drum A so that the pull or tension on the apron A^3 depends upon the amount the spring is stressed by the rotation of the spindle. The spindle is driven by a small electric motor D through a worm gearing D^1 , D^2 which per- 115 120 125 130

mits the motor to drive the spindle in either direction but prevents the motor being driven by the spindle. The motor can be controlled in any convenient manner so as to adjust the tension on the apron to maintain the web tension at the correct value, but it is preferably controlled by one or other of the arrangements described in detail hereinafter.

In order that the tension on the apron may be suddenly increased, as for instance when the machine is stopped quickly, the end of the drum A, in which the bearing A¹ is mounted, is provided with a pulley-like flange A⁵ having an external friction surface A⁶ adapted to be engaged by a cam nose E¹ on a lever E which is pivoted to a lever E² carried freely on the spindle B. The lever E is normally maintained in its inoperative position, in which the nose E¹ is disengaged from the surface A⁶, by a spring F (Figure 3) which holds the levers E and E² against a fixed stop F¹. The lever E is moved into its operative position by a solenoid F² the plunger of which is connected to the lever E by a pivoted link F³ and which, when energized, acts in the opposite direction to the spring F.

When the solenoid F² is energized the end of the lever E is pulled in the direction of the arrow G as indicated in Figure 3, so that it turns about its pivot and presses the nose E¹ against the friction surface A⁶. This has the effect of locking the levers E and E² together so that they form, in effect, a rigid member, and the continued pull of the solenoid F² acting on this rigid member rotates the drum A in the direction of the arrow G¹ positively and independently of the spring C. When the solenoid F² is deenergized the spring F moves the two levers in the opposite direction to the arrow G so that the lever E² engages the stop F¹ and then the lever E turns about its pivot sufficiently to cause the cam nose E¹ to disengage the surface A⁶ before this lever also engages the stop.

The solenoid may be controlled in any convenient manner but is preferably, as in the control arrangements to be described, so interlocked with the switch or circuit-breaker controlling the main motor driving the printing press, or with the "stop" control device of the main motor, that it is automatically operated when the circuit of the motor is opened.

In the preferred form of control arrangement indicated by the square D⁸ in Figure 1 and shown diagrammatically in Figure 4 the armature D³ of the tension motor D is connected on one side to the mid-wire H of a three-wire direct current supply circuit having positive and negative outer wires H¹ and H² respectively. The shunt field D⁴ of the motor is permanently connected to the mid-wire H and the positive outer H¹.

The other side of the armature D³ of the

motor is connected, through a contact J¹ of a relay J, the contact J¹ being closed when the relay is in its deenergized position, to the handle K of a face-plate controller having a number of contacts K¹—K¹¹ arranged so that the handle can be rotated to engage any one contact. In order to ensure that the handle K may always rest directly on a contact and cannot remain in an intermediate position between two contacts, an arm L pivoted on the frame of the controller is provided with a spring L¹ arranged so that a roller L² on the end of the arm is pressed between the teeth of a star wheel L³ carried by the controller handle K.

The contacts K¹—K¹¹ are connected through a multi-core cable K¹²—indicated in dotted lines—to the corresponding contacts M¹—M¹¹ of a controller, hereinafter referred to as the follow-up controller, which is provided with a rotatable disc M corresponding to the handle K. The follow-up controller is mounted on a bracket X⁶ on the printing machine X adjacent the tension motor D whilst the hand-operated controller can be arranged at any suitable remote point.

The disc M of the follow-up controller is of insulating material and is provided with two circumferential conducting segments N, N¹ which are sufficiently long to engage all but one of the contacts M¹—M¹¹ simultaneously, the segments being separated from one another by insulating strips N² and N³ having a width slightly greater than that of one contact. The segment N is connected to the positive outer H¹ of the supply circuit and the segment N¹ to the negative outer H². The disc M is mechanically connected to the tension motor by a chain N⁴ and suitable reduction gearing.

In the preferred form of follow-up controller shown in Figure 5 the segments N, N¹ are arranged on the circumference of the disc M so that they are engaged by spring contacts, one of which is shown at M¹, projecting from a fixed disc O of insulating material mounted behind the disc M. The disc M is rigidly mounted on a shaft O¹ which is driven through reduction gearing O², O³ and O⁴ by the chain N⁴, the whole controller being mounted in a casing O⁵.

In describing the operation of the control arrangement it will be assumed that when the motor armature D³ is connected to the positive outer H¹ it rotates the spindle B in the direction of arrow G¹ in Figure 3 and thus tightens the spring C and increases the web tension, whilst when it is connected to the negative outer H² it rotates to decrease the web tension.

The setting of the controllers is arranged so that during normal operation a suitable value of web tension is obtained when the handle K is on, say, the centre contact K⁶, the gearing O², O³, O⁴ and the chain N⁴ being

arranged so that the corresponding contact M^6 on the follow-up controller engages the insulating strip N^2 between the segments N , N^1 . In this position, in which the controllers are shown in Figure 4, the web tension remains constant since the circuit of the motor is open at the strip N^2 .

In order to increase the web tension the handle K is rotated in a counter-clockwise direction, say to the next contact K^5 , so that a circuit is completed for the motor from the handle K , its contact K^5 , the contact M^5 of the follow-up controller and the segment N to the positive outer H^1 . The motor now rotates the spindle B to increase the web tension and, at the same time, drives the disc M in a clockwise direction until the contact M^5 leaves the segment N and engages the strip N^2 . The motor circuit is then opened and the motor stops, the web tension remaining constant at the new value.

Further movements of the handle K in a counter-clockwise direction cause further increases in web tension, the motor being stopped after each movement of the handle as soon as the insulating strip N^2 engages the corresponding contact of the follow-up controller. If the handle K is moved in a clockwise direction, say from the position shown to the contact K^7 , the circuit of the motor is completed through the contact M^7 and the segment N^1 to the negative outer H^2 . The motor accordingly rotates the spindle B to decrease the web tension, the disc M rotating in a counter-clockwise direction until the contact M^7 engages the strip N^2 and the motor stops.

The tension of the apron depends directly on the tensioning of the spring which in turn varies, within normal limits, with the number of turns of the spindle. Hence it will be apparent that since the disc M has a definite position corresponding to each position of the motor D and the spindle B , that is to each value of web tension, and that since this position corresponds to the position of the handle K , the position of this handle provides a visual indication of the value of the web tension. Thus the contacts K^1-K^{11} can, if desired, be calibrated to indicate in pounds, or other suitable units, the value of web tension for each position so that the handle can be set by an operator to give any desired value of web tension.

It is usually found desirable in practice to reduce the web tension while a join is being made between the paper from a new reel and that from the old reel which is almost emptied. Such joins are made when the press is running slowly, this slow running being obtained by switching off the main motor X^3 and driving the press from the auxiliary motor X^5 .

The web tension can obviously be adjusted to the desired reduced value when the speed

of the machine is reduced prior to making a join and restored to normal value as soon as the speed of the machine is increased again, by moving the handle of the controller to the appropriate contact.

It is, however, desirable that these changes before and after the join is made, should be automatic. Accordingly an additional connection is provided between the armature D^3 and the wire joining those contacts of the controllers, say the contacts K^9 and M^9 , which correspond to the value of web tension required for slow speed running, this additional connection including a contact J^2 of the relay J which is closed when the relay is in its energized position. The circuit of the relay J is controlled by the auxiliary contact P on the main motor switch Y^2 (Figure 1) and the auxiliary contact P^1 on the auxiliary motor switch Y^4 .

Thus when the auxiliary motor is brought into operation and the main motor switch opened prior to making a join, the contacts P and P^1 are closed to complete the energizing circuit of the relay J which accordingly operates to open the contact J^1 and to close the contact J^2 . The circuit of the armature D^3 of the tension motor through the handle K is thus opened at the relay contact J^1 and the handle K is rendered inoperative. The armature D^3 is however connected through the relay contact J^2 to the contact M^9 of the follow-up controller and thence through the segment N^1 to the negative outer H^2 so that the motor rotates to reduce the web tension until the disc M is moved to the position in which the strip N^2 engages the controller contact M^9 . As soon as the join has been made the main motor switch Y^2 is again closed, thus opening the auxiliary contact P and deenergizing the relay J . The armature D^3 is disconnected from the controller contact M^9 and connected to the handle K by the opening and closing of the relay contacts J^2 and J^1 respectively. The tension motor is thus connected to the positive outer H^1 and rotates to restore the web tension to its normal operating value as determined by the position of the handle K .

The solenoid F^2 for increasing the tension on the apron for braking purposes is controlled by the main control circuit of the machine so that it is energized when the "stop" push-button of the machine is operated. Thus a stop relay R is normally energized from the supply circuit H , H^1 through a holding circuit including a contact R^1 of the relay, which is closed when the relay is energized, and a "stop" push-button R^4 . The relay R is provided with additional contacts R^2 and R^3 which are respectively closed and open when the relay is energized. The contact R^2 controls the circuit of a holding coil Y^6 for the switch Y^2 so that this switch is held in its closed position, the circuit of the

coil Y^6 being opened to allow the switch to open and stop the machine when the relay R is deenergized. The contact R^3 acts to complete the circuit of the solenoid F^2 when the relay is deenergized.

When the push-button R^4 is depressed the holding circuit of the relay R is opened so that this relay deenergizes to open the contact R^2 , to stop the machine, and to close the contact R^3 to energize the solenoid F^2 to increase the web tension for braking in the manner described above. When the machine stops, its main control gear Y^3 (Figure 1) is returned to the start position in which the auxiliary contact P^2 is closed, this contact completing a pick-up circuit for the relay R so that, provided the button R^4 has been released, this relay is energized and operates to open the circuit of the solenoid F^2 at the contact R^3 , to complete its own holding circuit at the contact R^1 and to close the circuit of the holding coil Y^6 at the contact R^2 so that the machine can be restarted when desired.

It will be noted that when the main motor is stopped and the auxiliary motor started for making a join, the push-button R^4 can be used to stop the main motor and the solenoid F^2 will act to increase the web tension during slowing up of the machine irrespective of the position of the spindle B and the movements of the motor to decrease the web tension, the solenoid F^2 being deenergized as soon as the main motor stops so that the web tension resumes the appropriate value for slow speed running as determined by the follow-up controller in the manner described above.

In the alternative control arrangement shown in Figure 6 a tension motor D is employed having an armature D^5 and two oppositely wound series field coils D^6 , D^7 , one or other of which is operative when the motor rotates to vary the web tension. In the following description it will be assumed that when the motor armature D^5 is connected to the direct current supply circuit H^3 , H^4 in series with the field coil D^6 the motor rotates the spindle B in the direction of the arrow G^1 (Figure 3) to increase the web tension, whilst when the field coil D^7 is used the motor rotates in the opposite direction to decrease the web tension.

One side of the armature D^5 is connected to the supply conductor H^3 and the other side to one end of each field coil. The other end of the field coil D^6 is connected to the other supply conductor H^4 in series with a limit switch S , which is operated by the spindle B in a manner to be more fully described to prevent the web tension being increased beyond a predetermined value, and an "increase" push-button switch T . The other end of the field coil D^7 is connected to the supply conductor H^4 in series with a limit switch S^1 , which prevents the web tension being reduced below

a predetermined value, and a "reduce" push-button switch T^1 .

Thus the push-buttons T and T^1 , which can be arranged at any suitable remote point, when operated respectively cause the motor to rotate to increase the web tension and to decrease the web tension, the maximum value of the web tension being controlled by the setting of the limit switch S and the minimum value by the setting of the limit switch S^1 .

The limit switches S S^1 may be operated in any desired manner to prevent the motor D rotating the spindle B too far in either direction from a normal position but these switches are preferably constructed and arranged as shown in Figure 7 so that they are operated by a nut which travels on a screw-threaded portion of the spindle B . As shown in this figure the spindle B is provided with a screwthreaded portion B^2 at one end for a nut B^3 which engages a fixed guide (not shown) arranged so as to prevent the nut from rotating but to permit it to travel along the screwthreaded portion B^2 as the spindle B is rotated. The screwthreaded portion B^2 may be disposed at either end of the spindle B but is preferably at the end adjacent the worm wheel D^2 as indicated in dotted lines in Figure 2.

The switches S and S^1 are carried on an insulating support U , arranged below the screwthreaded portion B^2 , each switch consisting of a pivoted arm U^1 which is normally held in engagement with a contact stud U^2 by a spring U^3 but which is rocked about its pivot to disengage the stud when an upwardly projecting lug U^4 on the arm U^1 is engaged by a pin B^4 on the nut B^3 as this nut travels along the screwthreaded portion B^2 .

When the motor rotates the spindle in the direction of the arrow G^1 (Figure 3) to increase the web tension the nut travels along the screwthreaded portion B^2 towards the switch S and, if the push-button T is held closed, the motor continues to rotate until the pin B^4 engages the lug U^4 of the switch S , thus opening this switch and stopping the motor.

The web tension remains at the maximum value, as determined by the position of switch S , until the push-button T^1 is depressed to cause the motor to rotate in the opposite direction, the web tension being reduced to its minimum value if the button T^1 is held closed until the pin B^4 engages the lug U^4 of switch S^1 . It will be appreciated that the initial position of the nut B^3 on the screwed spindle and the switches S and S^1 can be arranged so that the maximum and minimum values of web tension are fixed at any desired amount.

As in the arrangement shown in Figure 4, auxiliary circuits can be provided for causing the web tension to be reduced automatically when the machine is driven at slow

speed by the auxiliary motor and to be increased again as soon as the normal running conditions are resumed.

This automatic control is effected by two relays V and W and two limit switches S² and S³ operated by the nut B³ in a similar way to the switches S and S¹. The relay V is controlled by the auxiliary contact P on the main motor switch Y² which is open when the contactor is closed so that under normal running conditions, with the main motor driving the machine, the relay V is in its de-energized position. The relay W is controlled by the auxiliary contact P¹ on the auxiliary motor switch Y⁴ which is open when the contactor is open so that under normal running conditions this relay is also in its de-energized position. The relay V is provided with contacts V¹ and V² which are respectively closed and open when the relay is de-energized and the relay W with contacts W¹ and W² both of which are open when the relay is de-energized.

The limit switches S² and S³ may be mounted on the insulating support U (Figure 7) on the opposite side of the spindle to the switches S and S¹ so that they are actuated by a pin, similar to the pin B⁴, on the opposite side of the nut B³. The switch S² is arranged so that it is opened by the pin when the web tension is at its normal operating value whilst the switch S³ is arranged to be opened when the web tension is reduced to the appropriate value for slow speed running.

The auxiliary circuits consist of a shunt or bridging circuit for the "increase" push-button T which connects the end of the motor field coil D⁶ to the supply conductor H⁴ through the limit switches S and S² and the contacts V¹ and W¹ of the relays V and W respectively, and of a shunt circuit for the "reduce" push-button T¹ which connects the end of the motor field coil D⁷ to the conductor H⁴ through the limit switches S¹ and S³ and the relay contacts V² and W², these shunt circuits being operative during the transition period to short-circuit one or other of the push-buttons and complete the circuit of the motor through one or other of the field coils so that it rotates in the appropriate direction.

During normal operation the main motor switch Y² is closed and the auxiliary motor switch Y⁴ open so that relays V and W are de-energized and the shunt circuit for the push-button T is open at the limit switch S² and relay contact W¹ whilst the shunt circuit for the push-button T¹ is open at the relay contacts V² and W². The web tension can thus be controlled by the push-buttons.

When a join is to be made the auxiliary motor switch Y⁴ is closed (before the main motor switch Y² is open to ensure a smooth transference of drive) thus completing at the contact P¹ the energizing circuit of the relay

W which operates to close its contacts W¹ W². No change in web tension takes place, however, as the shunt circuit of the push-button T is open at the limit switch S². The main motor switch is then opened, thus shutting down the main motor X³ and completing at the contact P the circuit of the relay V which operates to open its contact V¹ and close its contact V², thus completing the shunt circuit of the push-button T¹. The motor D then rotates to decrease the web tension until, when it reaches the appropriate value, the limit switch S³ opens and the motor is stopped.

As soon as the join has been made, the main motor switch Y² is again closed thus deenergizing the relay V which acts to open its contact V² and to close, at its contact V¹, the shunt circuit of the push-button T. The motor D then rotates to increase the web tension until, when it reaches the normal operating value, the limit switch S² opens. The auxiliary motor switch Y⁴ is then opened to allow the motor X⁵ to come to rest and to deenergize relay W which at its contacts W¹ and W² opens further points in the two shunt circuits so that complete control of the web tension is obtained by the push-buttons independently of the limit switches in their bridging circuits.

As in the arrangement shown in Figure 4, the solenoid F² for suddenly increasing the web tension when the machine is stopped is controlled by a normally energized stop relay R. If desired, however, this solenoid may be controlled by additional contacts on the relays V and W arranged so that the solenoid is energized when the relay V is energized and the relay W de-energized, that is, when both the main motor and auxiliary motor switches are open.

It will be appreciated that the above description is by way of example and that various modifications may be made both in the constructional details of the drum and spindle and also in the control arrangements within the scope of the invention.

Thus, for example, the helical spring between the spindle and the drum may be a closely wound helix with its turns practically touching, in which case the collar by means of which one end of the spring is connected to the spindle may be keyed to but slidable along the spindle so as to allow for the necessary end movement of the spring when the spindle is rotated. Again, the mechanism for producing the sudden increase in the tension of the apron during stopping of the machine may be so constructed that when put into operation it acts as a rigid connection between the spindle and the drum, the drum being then directly driven by the motor which usually drives it through the spring coupling.

When the machine is driven by a two-speed motor instead of a duplex motor equipment

consisting of a main and an auxiliary motor, the auxiliary contacts which, in the control arrangements described, act to cause the automatic change in web tension during the 5 change in speed of the motor are arranged in the appropriate manner on the change speed switch or switches of the motor.

In the control arrangement employing the hand-operated and follow-up controller the 10 follow-up controller may be provided with a rotating member having the segments on the face instead of the periphery thereof and the cooperating contacts suitably modified, whilst in the push-button control arrangement a tension motor may be employed which has a 15 single field winding and two independent armatures or armature windings arranged so that when one armature winding is energized the motor rotates in one direction and when 20 the other armature winding is energized the motor rotates in the other direction.

It will also be understood that either control arrangement may have the hand-operated control device, i. e. the controller handle 25 or push-buttons, as the case may be, supplemented by a device which operates to control the motor automatically in accordance with the web tension. Such an automatic control device may consist of a spring-controlled 30 guide or tension roller, over which the web passes on its way to the printing machine, this roller being arranged to operate the control handle or push-buttons through some 35 form of clutch or like coupling which will permit the motor to be controlled manually, independently of the automatic control, when desired.

What we claim as our invention and desire 40 to secure by Letters Patent is:—

1. For use with a printing machine having a main driving motor the combination with a stop switch for the motor of web-tensioning and controlling mechanism comprising a braking apron attached at one 45 end to a fixed point, a drum to which the other end of the apron is attached, a spindle for the drum, a spring for coupling the drum to the spindle, an electric motor operatively connected to the spindle, means for 50 energizing the motor and means for rotating the drum independently of the spring coupling to increase the tension on the apron suddenly, such means comprising a pivoted catch lever acting directly on the drum, an operating solenoid therefor and means for 55 energizing the solenoid controlled by the stop switch whereby the solenoid is energized to actuate the lever when the switch is operated to stop the main driving motor.

2. Web-tensioning and controlling mechanism for printing and like machines comprising, in combination, a braking apron attached at one end to a fixed point, a drum to 60 which the other end of the apron is attached, a spindle for the drum, a spring

for coupling the drum to the spindle, an electric motor operatively connected to the spindle, means for energizing the motor and limit switches operated by the spindle for rendering the said energizing means ineffective when the spindle has rotated a predetermined amount in either direction from its 70 normal position.

3. Web-tensioning and controlling mechanism for printing and like machines comprising, in combination, a braking apron attached at one end to a fixed point, a drum to which the other end of the apron is attached, a spindle for the drum, a spring for coupling the drum to the spindle, an electric motor operatively connected to the spindle, 75 a source of supply for the motor, a hand-operated controller for the motor and a device controlled in accordance with the apron tension, the arrangement being such that the device acts to disconnect the motor from the source of supply when the position thereof corresponds to the position of the controller whereby the position of the controller affords a direct indication of the apron tension. 80

4. Web-tensioning and controlling mechanism for printing and like machines comprising, in combination, a braking apron attached at one end to a fixed point, a drum to which the other end of the apron is attached, a spindle for the drum, a spring for coupling the drum to the spindle, an electric motor operatively connected to the spindle, and means for energizing the motor including a hand-operated controller and a follow-up controller driven by the spindle, the arrangement of the controllers being such that the follow-up controller disconnects the motor from the energizing means when the apron tension corresponds to the setting of the hand-operated controller. 85

5. Web-tensioning and controlling mechanism for printing and like machines comprising, in combination, a braking apron attached at one end to a fixed point, a drum to which the other end of the apron is attached, a spindle for the drum, a spring for coupling the drum to the spindle, an electric motor operatively connected to the spindle, 90 a source of supply for the motor, a hand-operated controller for the motor, a series of contacts thereon, a handle on the controller adapted in each position to engage one of such contacts, a follow-up controller, a series of contacts thereon, connections between corresponding contacts of the two controllers, a contact device on the follow-up controller driven by the spindle and adapted in each position to engage all but one of the contacts of said follow-up controller, and means for connecting the motor to the supply source and the controllers whereby the motor is inoperative when the disengaged contact of the follow-up controller corresponds to the 95 100 105 110 115 120 125 130

contact engaged by the handle of the hand-operated controller.

6. For use with a printing or like machine having a normal and a slow speed, a web-tensioning and controlling mechanism comprising in combination a braking apron attached at one end to a fixed point, a drum to which the other end of the apron is attached, a spindle for the drum, a spring for coupling the drum to the spindle, an electric motor operatively connected to the spindle, means for energizing the motor, a hand-operated controller for the motor, a follow-up controller driven by the spindle, the arrangement of the controllers being such that the follow-up controller disconnects the motor from the energizing means when the apron tension corresponds to the setting of the hand-operated controller, and means whereby the electric motor is automatically connected to the energizing means to decrease the apron tension to a predetermined reduced value during a change in speed of the printing machine from normal to slow speed.
- 10 7. For use with a printing or like machine having a normal and a slow speed the combination with control switches for selecting the speed of the machine, of web-tensioning and controlling mechanism comprising a braking apron attached at one end to a fixed point, a drum to which the other end of the apron is attached, a spindle for the drum, a spring for coupling the drum to the spindle, an electric motor operatively connected to the spindle, means for energizing the motor, a hand-operated controller for the motor, a series of contacts thereon, a handle on the controller adapted in each position to engage one of such contacts, a follow-up controller, a series of contacts thereon, connections between corresponding contacts of the two controllers, a contact device on the follow-up controller driven by the spindle and adapted in each position to engage all but one of the contacts of said controller, auxiliary contacts on the control switches for selecting the speed of the machine, and means for connecting the motor, the controllers, the auxiliary contacts and the energizing means whereby the motor is inoperative when the disengaged contact of the follow-up controller corresponds to the contact engaged by the handle on the hand-operated controller, and when the auxiliary contacts are actuated by the operation of the control switches to change the speed of the machine the motor is connected to the energizing means through the appropriate contacts of the controllers independently of the handle or the driven contact device so that the motor operates automatically during such change in speed to decrease or increase the apron tension according as the speed of the machine is re-

spectively changed from normal to slow speed or from slow speed to normal speed.

8. Web-tensioning and controlling mechanism for printing and like machines comprising, in combination, a braking apron attached at one end to a fixed point, a drum to which the other end of the apron is attached, a spindle for the drum, a spring for coupling the drum to the spindle, an electric motor operatively connected to the spindle, means for energizing the motor, a hand-operated controller for the motor, a follow-up controller driven by the spindle, the arrangement of the controllers being such that the follow-up controller disconnects the motor from the energizing means when the apron tension corresponds to the setting of the hand-operated controller, and means for rotating the drum independently of the spring coupling to increase the tension on the apron suddenly.

9. For use with a printing or like machine having a normal and a slow speed, web-tensioning and controlling mechanism comprising, in combination, a braking apron attached at one end to a fixed point, a drum to which the other end of the apron is attached, a spindle for the drum, a spring for coupling the drum to the spindle, an electric motor operatively connected to the spindle, means for energizing the motor, a hand-operated controller for the motor, a follow-up controller driven by the spindle, the arrangement of the controllers being such that the follow-up controller disconnects the motor from the energizing means when the apron tension corresponds to the setting of the hand-operated controller, means whereby the motor is connected to the energizing means to decrease the apron tension to a predetermined reduced value during a change in speed of the printing machine from normal to slow speed and means for rotating the drum independently of the spring coupling to increase the tension on the apron suddenly.

10. For use with a printing or like machine having a normal and a slow speed, web-tensioning and controlling mechanism comprising, in combination, a braking apron attached at one end to a fixed point, a drum to which the other end of the apron is attached, a spindle for the drum, a spring for coupling the drum to the spindle, an electric motor operatively connected to the spindle, means for energizing the motor, two switches for controlling the motor, the arrangement being such that when one switch is operated the motor rotates in one direction to increase the apron tension whilst when the other switch is operated the motor rotates in the other direction to decrease the apron tension and means whereby the motor is automatically connected to the energizing means independ-

ently of the switches so that it rotates to decrease the apron tension to a predetermined reduced value during a change in speed of the printing machine from normal to slow speed 5 and to restore the apron tension to the normal value during a change from slow to normal speed.

11. For use with a printing or like machine having a normal and a slow speed the combination with control switches for selecting the speed of the machine of web-tensioning and controlling mechanism comprising, a braking apron attached at one end to a fixed point, a drum to which the other end of the apron 15 is attached, a spindle for the drum, a spring for coupling the drum to the spindle, an electric motor operatively connected to the spindle and having an armature and two oppositely wound field circuits, a source of supply 20 for said motor, two push-button switches for controlling the motor respectively arranged to connect the armature of the motor to the source of supply in series with one or other of the two field circuits, auxiliary contacts 25 on the control switches, and means controlled by said auxiliary contacts for connecting the motor armature to the source of supply in series with the appropriate field circuit and independently of the push-button switches to cause the apron tension to be decreased during a change in the speed of the printing machine from normal to slow speed and to be increased during a change from slow to normal speed.

35 12. For use with a printing or like machine having a normal and a slow speed, web-tensioning and controlling mechanism comprising, in combination, a braking apron attached at one end to a fixed point, a drum to which the other end of the apron is attached, a spindle for the drum, a spring for coupling the drum to the spindle, an electric motor operatively connected to the spindle, means for energizing the motor, two switches for controlling the motor, the arrangement being such that when one switch is operated the motor rotates in one direction to increase the apron tension whilst when the other switch is operated the motor rotates in the other direction to increase the apron tension, means whereby the motor is automatically connected to the energizing means independently of the switches so that it rotates to decrease the apron tension to a predetermined reduced value during a change in speed of the printing machine from normal to slow speed and to restore the apron tension to the normal value during a change from slow to normal speed, and limit switches operated by the 50 drum spindle and arranged to disconnect the motor from the source of supply when the apron tension attains a predetermined value as a result of the automatic operation of the motor during a change in speed of the machine.

13. For use with a printing or like machine having a normal and a slow speed the combination with control switches for selecting the speed of the machine, of web-tensioning and controlling mechanism, comprising, a 70 braking apron attached at one end to a fixed point, a drum to which the other end of the apron is attached, a spindle for the drum, a spring for coupling the drum to the spindle, an electric motor operatively connected to the spindle and having an armature and two oppositely wound field circuits, a source of supply 75 for said motor, two push-button switches for controlling the motor respectively arranged to connect the armature of the motor to the source of supply in series with one or other of the two field circuits, auxiliary contacts on the control switches, means controlled by said auxiliary contacts for connecting the motor armature to the source of supply in series with the appropriate field circuit and independently of the push-button switches to cause the apron tension to be decreased during a change in the speed of the printing machine from normal to slow speed and to be increased during a change from slow to normal speed, and limit switches operated by the 80 drum spindle and arranged to disconnect the motor from the source of supply when the apron tension attains a predetermined value as a result of the automatic operation of the motor during a change in speed of the machine.

14. Web-tensioning and controlling mechanism for printing and like machines comprising, in combination, a braking apron attached at one end to a fixed point, a drum to which the other end of the apron is attached, an electric motor, means for connecting the motor to the drum, a source of supply for said motor, a hand-operated controller for the motor, a follow-up controller driven by the motor, and means for connecting the motor to the source of supply in series with the controllers whereby the follow-up controller acts to render the motor inoperative when the two controllers are in corresponding positions.

15. Web-tensioning and controlling mechanism for printing and like machines comprising, in combination, a braking apron attached at one end to a fixed point, a drum to which the other end of the apron is attached, an electric motor, means for connecting the motor to the drum, a source of supply for said motor, a hand-operated controller for the motor, a follow-up controller driven by the motor, means for connecting the motor to the source of supply in series with the controllers whereby the follow-up controller acts to render the motor inoperative when the two controllers are in corresponding positions, and means for increasing the apron tension suddenly independently of the motor.

16. Web-tensioning and controlling mechanism for printing and like machines comprising, in combination, a braking apron means including an electric motor for varying the tension of the apron, a source of supply for said motor, and a control system for the motor comprising a hand-operated controller for the motor, a series of contacts thereon, a handle on the controller adapted in each position to engage one of such contacts, a follow-up controller, a series of contacts thereon, connections between corresponding contacts of the two controllers, a contact device on the follow-up controller driven by the motor and adapted in each position to engage all but one of the contacts of said follow-up controller, and means for connecting the motor to the supply source and the controllers whereby the motor is inoperative when the disengaged contact of the follow-up controller corresponds to the contact engaged by the handle of the hand-operated controller.
17. In a printing or like machine the combination of a main motor for driving the machine at normal speed, an auxiliary motor for driving the machine at slow speed, a source of supply for said motors, a main switch for connecting the main motor to the source of supply, an auxiliary switch for connecting the auxiliary motor to the source of supply, auxiliary contacts on each of said switches, a braking apron for the machine attached at one end to a fixed point, a drum to which the other end of the apron is attached, a spindle for the drum, a spring for coupling the drum to the spindle, a tensioning motor operatively connected to spindle, a source of supply for said motor, a hand-operated controller for the motor, a series of contacts thereon, a handle on the controller adapted in each position to engage one of such contacts, a follow-up controller, a series of contacts thereon, connections between corresponding contacts of the two controllers, a contact device on the follow-up controller driven by the spindle and adapted in each position to engage all but one of the contacts of said controller, means for connecting the tensioning motor, the controllers, the auxiliary contacts and the source of supply for the tensioning motor, whereby the motor is inoperative when the disengaged contact of the follow-up controller corresponds to the contact engaged by the handle on the hand-operated controller and, when the main switch is opened and the auxiliary switch is closed to change the speed of the machine from normal to slow speed, the auxiliary contacts on the switches are actuated to cause the motor to operate independently of the controllers to reduce the web tension to a predetermined value, and means for rotating the spindle independently of the spring coupling to increase the tension of the apron arranged so that it is brought into

operation when the main switch is opened to stop the machine.

In testimony whereof we have signed our names to this specification.

HENRY TAYLOR.
WILLIAM GIBSON.
